United States Patent Office.

CONYERS BUTTON, OF PHILADELPHIA, PENNSYLVANIA.

Design No. 4,251, dated July 19, 1870.

DESIGN FOR STOCKING FABRIC.

The Schedule referred to in these Letters Patent and making part of the same

---

I, CONYERS BUTTON, of Philadelphia, county of Philadelphia, State of Pennsylvania, have invented or produced a Design for a Stocking Fabric, of which the following is a specification.

The accompanying drawing represents sufficient of a stocking fabric to illustrate my design, the principal features of which are the central vertical stripe *a*, and on one side of the latter the stripes *b*, *c*, *d*, and *e*, and on the opposite side the strips *b'*, *c'*, *d'*, and *e'*, there being vertical spaces between these stripes, and in these spaces, and in the stripes, spots *f*, arranged in line with each other, so that they have the appearance of transverse stripes, which, combined with the vertical stripes, make the pattern of a plaid character.

Claim.

The design for a stocking fabric, substantially as described, and as illustrated in and by the accompanying drawing.

In testimony whereof I have signed my name to the specification in the presence of two subscribing witnesses.

CONYERS BUTTON.

Witnesses:

LOUIS BOSWELL,
WM. A. STEEL.
